DESIGN FOR A DICKEY

Sara Mirsky, New York, N. Y.

Application May 29, 1944, Serial No. 113,794

Term of patent 3½ years

(Cl. D3—25)

To all whom it may concern:

Be it known that I, Sara Mirsky, a citizen of the United States, residing in the city of New York, county of New York, and State of New York, have invented a new, original, and ornamental Design for a Dickey, of which the following is a specification, reference being had to the accompanying drawing, forming a part thereof.

The drawing is a front view of a dickey showing my design.

The back of the dickey is of conventional configuration.

I claim:

The ornamental design for a dickey, as shown and described.

SARA MIRSKY.
